UNITED STATES PATENT OFFICE.

JOHN THOMAS WRIGHT, OF BIGBYVILLE, TENNESSEE.

MECHANISM FOR OPERATING CHURNS.

SPECIFICATION forming part of Letters Patent No. 426,353, dated April 22, 1890.

Application filed December 31, 1889. Serial No. 335,514. (No model.)

To all whom it may concern:

Be it known that I, JOHN THOMAS WRIGHT, a citizen of the United States, residing at Bigbyville, in the county of Maury and State of Tennessee, have invented a new and useful Mechanism for Operating Churns, of which the following is a specification.

My invention relates to improvements in churn-powers; and it consists of certain specific constructions of the frame-work, as well as a peculiar means for adjusting the dasher-shaft upon and removably connecting it with the vertically-reciprocating power-rod, all as will be hereinafter more fully described.

15 In the drawings, Figure 1 is a side elevation of my improved device. Fig. 2 is a front elevation of the same. Fig. 3 is a section on the line 3 3 of Fig. 2. Fig. 4 is an enlarged section, on the line 4 4 of Fig. 1. Fig. 5 is a 20 detail view of the slotted guide.

The frame-work which carries the mechanism for actuating the churn-dasher consists of a flat base B, resting upon the floor, and upon which the churn-body is to be placed 25 and by its weight to steady the entire device and prevent it from tilting or falling over. From this base rises an upright U from four to six feet in length, which is secured at right angles to the base in any desired manner, and 30 which carries horizontally-projecting brackets K—one at its upper end and one at about its mid-length—both of which project out over the base B, and are provided near their outer edges with holes k.

35 The driving mechanism for imparting a reciprocatory motion to the churn-dasher, and which forms no part of my invention, consists of a heavy balance-wheel W, mounted upon the short shaft S', journaled in horizontal bearings to the upright U between the brackets K, a small gear-wheel g' upon the rear end of the shaft, a larger gearing wheel G', journaled in the upright so as to mesh with the smaller gear, a hand-crank Q, secured to the outer face of this larger gear-wheel, and a cranked pitman-rod P, one end of which engages one of a series of radial openings O in one of the spokes of the balance-wheel W, but may be adjusted to any 45 one of the other holes at a greater or less distance from the axle of said wheel, in order to give a greater or less throw to the free end of

the pitman-rod P, all as will be clearly understood by persons skilled in the art without more explicit description.

55 The letter R represents a "power-rod," so called, which is free to reciprocate vertically through the holes k in the brackets K, and this rod has a journal r at a proper point, in which the free end of the pitman-rod P is pivoted, whereby when the crank-arm Q is turned a rapid reciprocation vertically is imparted to the power-rod R. Heretofore this power-rod has been continued downwardly and provided with dashers near its lower end, and 60 was therefore adapted to act as a dasher-rod for a churn; but in such cases when it was desired to remove the body of the churn (which of course surrounded the dasher-shaft) the rod had necessarily to be disconnected 65 from the pitman-rod and from one or both of its bearings k, in order to allow its lower end sufficient lateral movement to withdraw the churn-body therefrom without spilling the 70 cream.

75 In the present invention I provide blocks L, preferably cut away on their rear faces l, adapted to fit the power-rod, and these blocks may be replaced by others of larger dimension, as hereinafter described. A guide G is 80 also provided, having a longitudinal slot S and having a concaved front face g, and these blocks L are interposed between said guide and the power-rod R at the upper and lower ends of the guide, bolts T being passed through 85 the three members and their heads seated in countersunk recesses in the cut-away portions g of the guide G.

The dasher-shaft D is of the usual construction, and in fact may be the ordinary dasher-shaft of almost any churn now manufactured 90 which is operated in this manner. Through the dasher-shaft I bore one or more ordinary gimlet-holes d, and an ordinary bolt is seated in the slot S of the guide G, with its head t' 95 upon the rear face of the guide between the two blocks L, its body T', loosely engaging said slot, passing through one of the gimlet-holes d in the dasher-shaft D, and carrying a hand-nut T² on its free outer end. It will be understood that the bolt T' can be engaged with 100 any one of several gimlet-holes with which the dasher-shaft may be provided, and also that by loosening the hand-nut T² a further

and more accurate adjustment between the guide and dasher-shaft can be made to the extent of the slot S. It will also be understood that when the body of the churn is of 5 a considerable diameter (much larger than is customary, however) the blocks L can be replaced by others much thicker, which will throw the guide G considerably farther from the upright U, and will therefore permit the 10 large-sized churn-body to rest upon the base B and still allow the dasher-shaft to pass down its axial line.

From the above description it will be seen that the weight of the churn-body and its 15 contents rigidly maintains the upright position of my improved churn-power; that by the use of the blocks L the device can be used in connection with churning having bodies of exceptionally-large diameter; that the device can 20 be connected with the dasher-shaft of any ordinary churn by simply boring a gimlet-hole in such shaft, and that when so connected the shaft may be disconnected therefrom, or may be vertically adjusted in the guide G 25 thereof by simply working the hand-nut T².

Especial stress is laid upon the vertically-reciprocating power-rod, which is guided in holes near the outer edges of the bracket K, and to which the pitman P is connected, as 30 the size of and bearings for this power-rod are especially constructed with a view to their greatest adaptability to this machine, and said power-rod is never removed from said bearings nor disconnected from said pitman, 35 as is necessary where the dasher-shaft is con-

nected directly to the pitman without the intervention of any power-shaft.

Having thus described my invention, I claim—

1. The combination, with the frame-work, a 40 vertically-reciprocating power-rod R therein, and a vertically-slotted guide G, having a concaved face g, carried by said power-rod, of the shaft D, the bolt T', its body engaging said slot and a hole in the shaft and its head t' on 45 the rear face of said guide, and a hand-nut T² on the forward screw-threaded end of said bolt, as set forth.

2. The base B, the upright U, supported thereby, and the forwardly-projecting brackets K K, having holes k k near their front edges, in combination with the vertically-reciprocating power-rod R, the shaft D, the guide G, having a concave face g, to which 50 said shaft is adjustably connected, the blocks L, having concave rear faces l, inserted between said power-rod and the rear face of said guide and supporting said guide beyond the line of the front edges of said brackets, and bolts T, passing through said rod, blocks, 55 and guide, and their heads countersunk in the concave face of the latter, as and for the purpose set forth.

In testimony that I claim the foregoing as my own I have hereto affixed my signature in 60 presence of two witnesses.

JOHN THOMAS WRIGHT.
